Primary Examiner — Anhdao Doan(74) *Attorney, Agent, or Firm* — Grant Anderson LLP(57) **CLAIM**

The ornamental design for a reagent reservoir, as shown and described.

DESCRIPTION

FIG. 1 shows a perspective view of a reagent reservoir;
FIG. 2 shows a top view of a reagent reservoir;
FIG. 3 shows a side view along the length of a reagent reservoir;
FIG. 4 shows a side view along the width of a reagent reservoir; and,
FIG. 5 shows a cut away view of a reagent reservoir, taken along the line 5-5 illustrated in FIG. 2.
